(57) **CLAIM**

The ornamental design for a combined pizza cutter and lifter, as shown and described.

DESCRIPTION

FIG. 1 is a top perspective view of a combined pizza cutter and lifter showing my new design;

FIG. 2 is a bottom perspective view of the combined pizza cutter and lifter of FIG. 1;

FIG. 3 is a top plan view of the combined pizza cutter and lifter of FIG. 1;

FIG. 4 is a bottom plan view of the combined pizza cutter and lifter of FIG. 1;

FIG. 5 is a side plan view of the combined pizza cutter and lifter of FIG. 1;

FIG. 6 is an alternate side plan view of the combined pizza cutter and lifter of FIG. 1;

FIG. 7 is an end plan view of the combined pizza cutter and lifter of FIG. 1;

FIG. 8 is an alternate end plan view of the combined pizza cutter and lifter of FIG. 1;

FIG. 9 is a top perspective view of the combined pizza cutter and lifter of FIG. 1 in an open position;

FIG. 10 is a bottom perspective view of the combined pizza cutter and lifter of FIG. 1 in an open position;

FIG. 11 is a top plan view of the combined pizza cutter and lifter of FIG. 1 in an open position;

FIG. 12 is a bottom plan view of the combined pizza cutter and lifter of FIG. 1 in an open position;

FIG. 13 is a side plan view of the combined pizza cutter and lifter of FIG. 1 in an open position;

FIG. 14 is an alternate side plan view of the combined pizza cutter and lifter of FIG. 1 in an open position;

FIG. 15 is an end plan view of the combined pizza cutter and lifter of FIG. 1 in an open position; and,

FIG. 16 is an alternate end plan view of the combined pizza cutter and lifter of FIG. 1 in an open position.

The oblique shade lines in the Figures show a transparent, reflective, or shiny surface, and not surface ornamentation.
